UNITED STATES PATENT OFFICE.

FREDERICK A. YOUNG, OF AURORA, INDIANA.

WAGON-BRAKE.

SPECIFICATION forming part of Letters Patent No. 398,303, dated February 19, 1889.

Application filed July 2, 1888. Serial No. 278,868. (No model.)

To all whom it may concern:

Be it known that I, FREDERICK A. YOUNG, a citizen of the United States, and a resident of Aurora, in the county of Dearborn and 5 State of Indiana, have invented certain new and useful Improvements in Wagon-Brakes; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a representation of my improved brake and is a plan view thereof, and Fig. 2 is a side view.

This invention has relation to wagon-brakes; and it consists in the construction and novel 20 combination of devices, all as hereinafter set forth, and pointed out in the appended claims.

In the accompanying drawings the hounds of a wagon are shown, to which is secured a transverse bar, A, and a loop-plate, B, the bar 25 A being secured upon the front straight portion, C, of said plate B. The rear or bowed portion, D, of said plate extends backward over the hounds, and is formed with a narrow offset-loop, E, which is located over the mid- 30 dle bar or coupling-pole and which is provided with lugs F F, carrying the pivots forming the fulcrum of a short loop-lever or link-lever, G.

H H are guards attached to the plate B and 35 bar A and extending along the sides of said plate over the operating-lever L.

I is a ratchet-catch, which is provided with an eye, a, at one end to engage a ring, b, of the plate B, and with a stud, C, at its other 40 end to engage perforations d of said plate when in position thereon. When so placed, its teeth are upward and serve to engage a pin of the brake-lever to hold it to its work. When not required—as, for instance, when 45 the bed is on the wagon—it is turned laterally out of the way, being then held by a hook, e, of the bar A. This leaves the operating-lever free to move backward and forward.

K is the transverse brake-bar, carrying the

shoes L L and connected to the ends of the 50 bar A by the link-hangers g. A clip, h, around the middle of the brake-bar receives through perforations in its branches the threaded end 55 of a rod, k, which extends longitudinally back to the loop-lever G. Nuts l l serve to secure the clip to the threaded end of the rod. The loop-lever G is formed, preferably, in two 60 branches, V V, isometrically bent outward to pass around the sides of the reach or coupling-pole, and having at their upper and lower ends lugs m, between which are pivoted, respectively, the short connection z and the rear end of the rod k, which extends to the clip of the brake-bar. The front end of the connection z is pivoted to the operating-lever L. By 65 this construction the strain in applying the brakes is confined to the plate B and transverse bar A and their lever-connections, and is independent of the coupling-pole or reach.

Having described this invention, what I 70 claim, and desire to secure by Letters Patent, is—

1. A brake-lever attachment consisting of the transverse bar A and the loop-plate B, a pivoted link-lever spanning the coupling-pole, 75 the rod k, the brake-bar, the main lever L, and the connection z from the main lever to the link-lever, substantially as specified.

2. The combination, with the rear hounds and the coupling-pole, of the plate B, carrying a pivoted link-lever spanning said coupling-pole, the operating-lever L, the threaded rod k and clip around the brake-bar, and the connection z, substantially as specified.

3. In a brake-lever attachment, the combination, with the lever L and the perforated plate B, having a ring, b, of the adjustable ratchet-catch I, engaging said ring at one end and provided at its other end with a stud, c, to engage the perforation of the plate B, substantially as specified.

In testimony whereof I affix my signature in presence of two witnesses.

FRED. A. YOUNG.

Witnesses:

HORACE PURCELL,
FRED C. STRUNK.
